UNITED STATES PATENT OFFICE

2,387,120

TOWER OR MAST CONSTRUCTION

Harold Cohen, Elizabeth, N. J.

Application April 4, 1944, Serial No. 529,438

2 Claims. (Cl. 189—26)

This invention relates to fabrication of towers, masts and analogous structures.

The principal object of the invention is the provision of means whereby component parts may be transported from shop to field and be quickly, easily and effectually connected with each other to form structures of the character mentioned for use where wanted. Also, to enable such structures to be dismantled so that the component parts may be removed and stored in comparatively small space when not in use.

Other objects of the invention will appear when the following specification is read in conjunction with the accompanying drawing, in which—

Fig. 1 is a side elevational view of a portion of a tower or mast embodying the features of the invention, some parts being broken away and shown partly in section and parts being juxtaposed to illustrate certain features of the fabrication.

Fig. 2 is a sectional view taken on the line 2—2 of Fig. 1.

Fig. 3 is a side view showing certain parts of the construction.

Fig. 4 is a sectional view taken on the line 4—4 of Fig. 3.

Fig. 5 is a side elevational view of a portion of the tower or mast to illustrate the possible use and arrangement of guys.

Fig. 6 is a view similar to Fig. 3, but showing a modification.

Fig. 7 is a sectional view taken on the line 1-1 of Fig. 6.

Fig. 8 shows a further modification.

In the drawing, by way of example, there is shown components of a tower or mast. The structure may be of any height and of any formation in cross section, the same being triangular in the present instance. The tower or mast is fabricated in accordance with the invention by means of devices and structural elements prefabricated in a shop and used with certain other elements which are provided to be integrated with such prefabrications to form the tower or mast.

Referring now more particularly to Fig. 5 of the drawing, it will be apparent the tower or mast includes three supports or legs 10 each consisting of sections 11 arranged end to end. These sections 11 and therefore the legs are rigidly connected to each other by means of the present invention as follows.

Tubular members 12 of similar size and shape are rigidly connected to each other by tie bars.

13. Each member 12 is round in cross-section and each tie bar is in the form of a channel iron of suitable length. The bars 13 are secured to the members 12 as by welding to rigidly hold 5 the members in spaced relation to each other, the parts forming a triangular unit 14 prefabricated in the shop, the same being best seen in Fig. 2. A suitable number of these units 14 are used according to the height of the tower or 10 mast desired.

Each of the leg sections 11 is round in cross-section to fit into a tubular member 12 and said section 11 may be of any preferred length although all sections 11 are advantageously of the same length. Each leg section 11 has collars 15 fixedly secured thereto near the opposite ends respectively. Of course, each of the lowermost and uppermost leg sections require a single collar. Each collar 15 has a radially disposed apertured lug 16. The lug 16 of the lower collar of each leg section 11 has connected therewith a rigid link or connector 17 by means of a pivot bolt or the like 18, so that the link may have pivotal movement. All of the links are applied in the shop to remain attached to the respective leg sections. Each link 17 is made from a single metal strip bent upon itself into U-shape to provide equal members 19 joined by a bight 20. The members 19 have registering holes 21 in the opposite ends thereof and those at one end of the link remote from the bight 20 to receive the bolt 18. A filler block 22 is secured between the members 19 and a hole 23 extends through the members 19 and the block 22 to receive one end of a guy line or the like 24 when the tower or mast is erected.

In erecting a tower or mast, a group of leg sections 11, three in number, have a unit 14 applied thereto in which the upper ends of the sections 11 are received in the tubular members 12 respectively, with the collars 15 abutting the lower ends of the members 12. A second group of leg sections 11 are inserted into the aforesaid members 12, respectively, with the lower collars 15 thereof abutting the upper ends of the members 12. The links 17 are then swung into engagement with the lugs 16 of the lower leg sections 11, bringing the bight 20 of each link into engagement with the related lug 16. A bolt 25 or the like is removably inserted in the registering holes 21 in members 19 near the bight 20 and the hole in the lug 16. In this manner one group of leg sections 11 is rigidly connected with another group in which the leg sections 11 are arranged end to end, the collars 15 abutting the

tubular members 12 and the inserted ends of the leg sections out of contact with each other, as indicated at 26. A repetition of these operations is carried out until the tower or mast of the desired height is fabricated. Any suitable number of guy lines 24 are connected with selected links 17 by virtue of the holes 23, as shown in Fig. 5.

In Figs. 6 and 7, a modification is shown in which a lug 30 of U-shape is used in lieu of the solid lug 16, and the lug 30 on each upper collar 15 has a tubular filler piece 31 welded in place to receive a plain bolt 32 which engages the bight 20 of the link 17. A split pin 33 extends through the lower end of the bolt 32 crosswise thereof and engages with said bight 20 to hold the bolt in place. A projection 34 on the bight 20 limits the pivotal movement of the link 17 to a position paralleling the tubular member 12, so that the bolt 32 may be properly employed to detachably hold the link 17 in the functioning position. In lieu of the filler block 22, there is provided an apertured lug 35 of U-shape on each tubular member 12. This lug 35 is long enough to project outwardly a sufficient degree between the members 19 of the link 17 for the securement of a guy line 24 to the lug 35 so that the strain will be borne by the unit 14 instead of the link

17. As shown in Fig. 8, this same result is obtained by an apertured lug 36 of single thickness in lieu of the lug 35 or block 22.

I claim:

1. A fabricated construction including pairs of supporting leg sections, tubular members, tie bars rigidly connected with said tubular members to maintain them in spaced relation to each other, collars fixed on said leg sections respectively, a 10 pair of said leg sections projecting into each of said tubular members in end to end relation with the collars thereof abutting the tubular member, and connecting means connected with the collars of each pair of leg sections to connect the latter 15 to each other, said connecting means including radial lugs on said collars respectively, and a U shape link having one end pivotally connected with one of said lugs and the opposite end of the link being detachably connected with the other lug.

2. A fabricated construction as set forth in claim 1, and lugs on said tubular members respectively, each of said lugs extending through the respective U shape link so that a guy line may 25 be attached to the lug.

HAROLD COHEN.
